[57] CLAIM

The ornamental design for a vehicle rear signal light lens, as shown and described.

DESCRIPTION

FIG. 1 is a front elevational view of a vehicle rear signal light lens showing our new design, the automobile being shown in broken lines for illustrative purposes only; FIG. 2 is an enlarged front elevational view of the lens of the new design;

FIG. 3 is a top plan view thereof;

FIG. 4 is a bottom plan view thereof; and

FIG. 5 is a side elevational view thereof.
